Primary Examiner — George A Bugg*Assistant Examiner* — David Weir(74) *Attorney, Agent, or Firm* — Cramer Patent & Design, PLLC.; Aaron R. Cramer(57) **CLAIM**

The ornamental design for a dolly as shown and described.

DESCRIPTION

FIG. 1 is a perspective top front right view of a dolly, showing my new design;

FIG. 2 is a perspective top rear left view thereof;

FIG. 3 is a left elevation view thereof;

FIG. 4 is a right elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines in the figures are for the purpose of illustrating portions of the dolly, which form no part of the claimed design.

1 Claim, 6 Drawing Sheets(56)
